UNITED STATES PATENT OFFICE.

ALBERT F. WINKLEY, OF FARIBAULT, MINNESOTA.

METHOD OF MAKING ARTIFICIAL LIMBS.

1,219,613.

Specification of Letters Patent. Patented Mar. 20, 1917.

Application filed May 22, 1915. Serial No. 29,735.

To all whom it may concern:

Be it known that I, ALBERT F. WINKLEY, a citizen of the United States, residing at Faribault, in the county of Rice and State 5 of Minnesota, have invented certain new and useful Improvements in Methods of Making Artificial Limbs, of which the following is a specification.

My invention relates to artificial limbs 10 and has for its object the manufacture of a seamless artificial limb formed of fiber. Fiber is an artificial material of general commercial use constructed of cellulose from cotton or from other fiber materials. It is 15 exceedingly hard, tough and durable and combines with these properties great lightness. When kept in water for a considerable period of time, in practice three or four days, the fiber becomes softened and 20 it then can be shaped or formed. Artificial limbs have in the past been made from fiber by employing sheet fiber and lapping the edges of the same over the limb form, or if tubular fiber has been used this has been 25 cut along one edge and the edges lapped during the forming period, said edges in either case afterward being trimmed to come flush and fastened with a binding. In the 30 practice of my invention I employ a tubular fiber shell. After the same has been properly softened I place the same over a special form, after which by winding a rope progressively over said form I am enabled to draw the shell into shape upon the form. 35 It will then harden in the form of artificial limb desired. The collapsible form comprises a central member which may readily be removed, after which the side members may be removed and a seamless, artificial 40 limb results.

It is important in this connection to note 45 that the winding of the rope about the form from the upper part toward the ankle has the result of moving material downwardly to the ankle portion of the limb, thereby much thickening the ankle portion while the larger upper portions are made correspondingly thinner. This results in strengthening 50 the limb at the point where the foot member is attached and the greatest strain takes place. The form or mold can be made of wood, iron or other material and, of course, a series of such molds will be necessary for shaping limbs of different sizes.

Each mold can, however, be used repeatedly 55 as it is in no respect injured by use.

The full objects and advantages of my invention will appear in connection with the detailed description thereof and are particularly pointed out in the claims. 60

In the drawings, illustrating the application of my invention in one form,—

Figure 1 is an elevational view of the cylindrical shell of which the artificial limb is made. Fig. 2 is a plan view of the same. 65 Fig. 3 is a side elevational view of the mold assembled. Fig. 4 is a top plan view of the mold assembled and Fig. 5 is a front elevational view of the same. Fig. 6 is a side elevational sectional view through the center 70 of the mold and limb showing the center member of the mold partly removed. Fig. 7 is a front elevational sectional view of 75 the limb and mold, one of the outer members of the mold shifted and ready to be removed from the limb. Fig. 8 is a plan section through the thicker portion of the limb and the mold showing the last two members of the mold shifted and ready to be withdrawn from the limb. Fig. 9 is a 80 side perspective view of the finished shell member of the artificial limb.

The following is my improved method of manufacturing seamless shell members of 85 artificial limbs.

A mold comprising a central member 10 having tapered sides and four or more outer members 11, 12, 13 and 14 fitting thereto is assembled and fastened together by means of the screws 15. The contour of the mold 90 exactly resembles that of the limb to be duplicated except that the diametral dimensions all differ from those of the original limb by the thickness of the shell.

A seamless cylindrical shell 16 of fiber or 95 other material of the nature of cellulose is slipped over the mold and is made pliable by the application of heat or water or other well-known methods. In practice it has been found that most effectively to soften 100 the ordinary commercial fiber it should be soaked in water three or four days before being applied to the form. The cylinder employed will be as large in diameter as the thickest part of the limb to be manufactured 105 and will just slip over the form. After the softened cylinder has been placed over the form a rope is wound progressively about

the cylinder from the top downward, as indicated diagrammatically in Fig. 3. The softened cylinder of fiber is thereby distorted and caused to shape itself to the 5 tour of the form. The distortion of material will have the effect of thickening the material at the ankle portion where the cylinder 16 must be reduced in diameter, as indicated at 20 in Fig. 6. After the softening 10 shell has thus been shaped to the form it will upon drying assume its rigid condition so that when the form is removed a perfectly-shaped seamless artificial limb of fiber results.

15 My invention provides a simple and effective means of removing the mold from the molded shell of the limb 18 as follows. The screws 15 are removed from the mold and the members of the mold are now held 20 together by the limb alone. Member 10 having tapered sides and being of the form of a truncated pyramid is first and most easily removed, withdrawing the same upward and vertically through the portion of 25 the limb having the larger aperture, as best shown in Fig. 6. Members 14 and 12 are first shifted to the center of the leg at 17, as indicated in Fig. 7; and then withdrawn 30 vertically and upward the same as member 10. Members 11 and 13 are then shifted to the center of the limb similarly to 12 and 14 at 19 and removed in an identical manner with the preceding members, leaving the shell member perfectly free from the mold 35 and the mold in a condition to be reassembled and reused. In some cases it may be desirable to cut the form so as to make nine pieces instead of five, as indicated in Fig. 4, there being corner pieces 21 as well as the 40 pieces heretofore referred to. This would additionally facilitate a withdrawal of the members 12, 14 and 11, 13.

The limb resulting from the practice of my invention will be light in a high degree 45 and at the same time extremely strong and durable. By thickening the material at the small ankle portion 20 of the limb it is possible to use a shell of relatively small thickness and thus additionally lighten the limb.

50 I claim:

1. The method of making artificial limbs which consists in soaking a cylinder of fiber until the same has become soft, placing the cylinder in place upon a mold, progressively

winding a cord about the cylinder from the 55 knee to the ankle and gradually increasing the tension in the cord toward the ankle to cause the walls of the cylinder to become distorted to thicken the stock at the ankle, drying the material while the same is so formed, 60 and thereafter removing the cord and withdrawing the mold, leaving a seamless member in the form desired.

2. The method of making artificial limbs which consists in soaking a cylinder of fiber 65 until the same becomes soft, placing the same in position upon a mold, progressively distorting and forming the cylinder upon the mold from one end thereof to the other while the same is softened to cause the walls of the 70 cylinder to become thickened at one end, drying the material to restore its rigidity while the same is so formed, and thereafter withdrawing the mold, leaving a seamless member of the form desired. 75

3. The method of making artificial limbs which consists in soaking a cylinder of fiber until the same has become soft, placing the cylinder in position upon the mold, progressively distorting and forming the cylinder 80 upon a mold from the knee end to the ankle to cause the ankle to become relatively thicker than the knee while the cylinder is softened, drying the material to restore its rigidity while the same is so formed, and thereafter 85 withdrawing the mold leaving a seamless member of the form desired.

4. The method of making artificial limbs which consists in soaking a cylinder of fiber until the same has become soft, placing the 90 cylinder in position upon a mold, progressively winding a circular flexible member about the cylinder from the knee to the ankle to form the cylinder about the mold and to draw down a portion of the material about 95 the knee toward the ankle to thicken the ankle while the cylinder is soft, drying the material while the same is so formed, and thereafter removing the flexible member and withdrawing the mold, leaving a seamless 100 member in the form desired.

In testimony whereof I affix my signature in presence of two witnesses.

ALBERT F. WINKLEY.
